UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

HUMIDIFIER

Application filed April 16, 1930. Serial No. 444,699.

The invention relates to humidifiers and primarily to devices of this character which are designed to moisten the air in a room or other compartment through the agency of heat supplied to a heat exchange device with which the humidifier is associated.

The invention has as its prime object the provision of a construction whereby fluid may be supplied for evaporation from a constant source of supply, the fluid being supplied as consumed by evaporation.

It is another prime object of the invention to combine a construction such as that just referred to with a radiator or other heat exchange device.

The invention also has as an object a construction such as that above referred to in which the moistening fluid is fed to a receptacle having combined therewith means whereby, when the receptacle is filled to a predetermined level, the excess fluid is discharged therefrom and employed to actuate a mechanism for shutting off the supply to the receptacle, the mechanism being automatically operable to again supply the receptacle with fluid when the liquid level therein is reduced below the desired or normal level.

Another object of the invention is to provide means for regulating the amount of fluid escaping from the source of supply.

The invention has these and other objects, all of which will be more readily understood when read in conjunction with the accompanying drawings which illustrate various arrangements which may be resorted to, it being, therefore, obvious that other changes and modifications may be resorted to without departing from the spirit of the appended claims forming a part hereof.

In the drawings, Fig. 1 is a front elevation of a heat exchange device mounted within a cabinet and providing means for heating a room or other compartment;

Fig. 2 is a section taken on line 2-2 of Fig. 1 on a slightly enlarged scale;

Fig. 3 is a section taken on line 3-3 of Fig. 1 also on a slightly enlarged scale;

Fig. 4 is a fragmentary rear elevation, par-

tially in section, of the structure illustrated in Figs. 1 and 2;

Fig. 5 is a section similar to Fig. 2 showing a modified arrangement which may be employed; and

Fig. 6 is a sectional view taken on the line 6-6 of Fig. 5.

As illustrated in the drawings, the structure whereby the various above enumerated advantages are obtained is associated with a radiator generally designated 10 having a heating fluid supply pipe 11 and a return pipe 12 connected therewith. The supply pipe 11 is connected with elements which, when associated with each other, provide what might be termed a header which is designated 13. The return pipe 12 is connected with elements 14 which are similar in construction and function to the elements forming the header 13. These headers 13 and 14 are connected with each other through the medium of a plurality of tubular passages 15 whereby the steam or other heating fluid supplied from the supply 11 may circulate and eventually be discharged from the radiator 75 through the return 12.

The radiator 10 may be mounted in a recess formed in a wall of a room or other compartment or may be housed within a housing 16, the radiator generally designated 10 being arranged within the housing in spaced relation to the opposite upper and lower ends thereof so as to provide openings designated 17 and 18, through the former of which air may be introduced to the casing, be heated 85 and circulated through the latter by convection. The radiator 10 may be formed of separate sections such as 19 or may be of an integral character. In either event, the rear face thereof will be provided with one or 90 more receptacles such as those designated 20 and 21. These receptacles are provided for the purpose of retaining a certain amount of liquid for evaporation by the application of heat applied by the radiator 10 to thus humidify the air contained in the room in which the structure is located. These receptacles 20 and 21 are supplied with fluid through the medium of a fluid supply pipe 22 which is connected to any suitable source of supply 100

such as 23. A valve 24 is located between these supply pipe connections to provide means for controlling the flow of liquid through the pipes 22 and 23. The upper 5 extremity of the supply pipe 22 is provided with a valve 35 which is employed to provide means for regulating the amount of liquid supplied to the receptacles such as 20 and 21. It will be noted that the outlet of the 10 supply pipe 22 is located directly above the receptacle 20 and, therefore, when the valves 24 and 25 are open, liquid will be supplied to the receptacle 20 through the valve 25. A tubular connection 26 is formed between the 15 receptacles 20 and 21 and one end such as 27 of the tubular connection 26 terminates below the edge of the receptacle 20 and, therefore, a certain prescribed amount of liquid will be retained for evaporation within this 20 receptacle. It is manifest that when the amount and level of the liquid in the receptacle 20 is in excess of a predetermined amount, that the excess liquid will then flow through the passage 26 into the receptacle 25 21. Another tubular passage designated 28 extends from the receptacle 21 to an element 29, the latter of which provides a chamber for the float 30. The tubular passage 28 extends into the receptacle 21 to adjacent the upper 30 edge thereof and thereby provides a means whereby excess liquid contained in the receptacle 12 is permitted to escape therefrom into the float chamber 29. As the liquid level in the float chamber rises, the float 30 is actuated to close the valve 31. This valve 31 is arranged in the supply pipe connection 22 and, therefore, when the liquid level in the chamber 29 reaches a required level, the valve 31 will automatically be closed, shutting off 35 the supply of fluid to the uppermost receptacle 20, the receptacle 21 and also the float chamber 29. It is manifest that when the liquid level in the float chamber 29 is reduced by evaporation, the valve 21 is again opened 40 which will allow fluid to be again fed to the receptacles 20 and 21 and the float chamber 29.

It is evident from the foregoing that the structure just described provides a means 50 for automatically supplying and maintaining a certain prescribed amount of liquid for evaporation and humidification from a constant source of supply.

The radiator or heat exchange device may 55 be formed to provide an integral structure or may be formed of separate sections which are connected with each other to provide a unit formed of separate sections. When the latter structure is employed, certain sections only may be provided with receptacles such as 20 and 21, it being understood that these receptacles may be cast integral with the sections designated 19.

To provide means for causing flow of liquid 60 from one of the receptacles to another later-

ally arranged adjacent receptacle, certain of said receptacles are provided with communicating openings which provide means whereby the liquid may flow from one receptacle to an adjacent or laterally disposed receptacle. By referring to Fig. 3, it will be noted that when the heat exchange unit is composed of separate sections, certain of the sections only are provided with receptacles such as 70 previously designated 20 and 21. When an arrangement such as this is resorted to, one of the receptacles is located in contacting relation to and in horizontal alignment with another and fluid from the supply pipe 22 is fed to one of the upper receptacles such as 75 30. One wall such as 32 of the receptacles 33 is arranged in contacting relation to a wall such as 32' of an adjacent receptacle such as 34 which, in turn, is arranged in a similar manner to the receptacle 36. Means is provided for supplying the receptacles such as 34 and 36 with liquid from the receptacle 33. This means, in the present instance, is designated 57 and 58 and consists of openings 80 which form a communication between the receptacles 33, 34 and 36. When this last mentioned arrangement is resorted to, the endmost receptacle such as 36 is provided with a discharge pipe or passage such as 26 through which excess liquid is fed therefrom 85 to receptacle 37 located immediately below the receptacle 36. It is understood that receptacles 38 and 39 similar to those designated 33 and 34 are located immediately below these last mentioned receptacles and each 90 is provided with a passage such as 40 and 41 whereby the liquid may flow from one to the other of said receptacles in the manner above referred to. A discharge pipe 28' extends from one of the lower receptacles such as 39 to the float chamber 42 which will cause 95 operation of a float controlled valve in the manner hereinbefore referred to.

It is understood that for simplicity of manufacture, certain of the radiator sections may each be provided with an element which forms a chamber, one of which provides a float chamber or a section including several heating fluid passages and superposed receptacles 20 and 21 and float chamber may be employed. The elements forming the receptacles generally designated 20 and 21 are respectively designated 42, 43 and 44 and are provided with communicating openings 45 and 46 whereby liquid introduced to the float chamber 44 may eventually find its way to the receptacle 42.

The structure above described may, if so desired, be provided with heat radiating fins 47 which extend into the casing or housing 16 and assist in heating the air introduced through the opening 17.

In the structure illustrated in Fig. 5, a fluid supply pipe 48 which is connected with a source of supply 49 is shown. A valve 50

- is located in this supply pipe and said valve is controlled through the agency of a float 51, the latter of which is located within a trough 52 forming a receptacle for the excess liquid 5 discharged from the nozzle 53. The arrangement just referred to contemplates the discharge of fluid from the nozzle in an upwardly direction directly against the rear face of the heat exchange unit 54 which will 10 cause evaporation of a portion of the liquid which is discharged through the opening 55 into the room or compartment in which said device is located and in addition, will assist to draw air to be heated into the space provided between the radiator 54 and the walls 15 of the casing in which the radiator is located. The excess liquid or condensate resulting from this mode of operation is gathered in the receptacle 52 and, therefore, when 20 the liquid in the receptacle reaches a certain predetermined level, the valve 50 will operate to prevent further flow of fluid through the pipe 48 and the nozzle 53 until the water contained in the receptacle 52 has evaporated 25 sufficiently to again lower the float 51. When the float is lowered the valve 50 is opened which again allows fluid to be introduced to the pipe or passage 48 from which it is ejected through the nozzle 53. A damper 56 30 may be provided to control the passage of heated air from the device and said damper may be actuated either manually or automatically. When it is desired to operate the damper automatically, a thermostat 57 having 35 a rod 58 forming a connection between the damper and thermostat is provided which will arrange the damper in various positions depending upon the temperature of the air traveling through the structure. The several receptacles such as 33, 34 and 36 and the receptacles 37 to 39 may be supplied with any water absorbent or retaining material which 40 will give off moisture as heat is applied.
- From the foregoing description of the invention, it is manifest that a construction is provided whereby moisture is intermittently supplied from a constant source of fluid supply and that the structure includes automatically operable means to control the flow 45 of fluid from the source to the receptacles forming part of the humidifier. It is also manifest that the utilization of a valve or other mechanism such as 25 provides means for regulating the amount of liquid or fluid fed to the receptacles in which latter the liquid is retained for evaporation.
- Having thus described the invention, what I claim and desire to cover by Letters Patent is:
1. In a device of the kind described the combination of a member providing a wall of a vertically arranged heat conducting air duct having an air inlet opening at one end and an air outlet opening at the opposite end, said member being provided with a passage 50 for a heating medium and being provided with a liquid receptacle which projects from one face of said member into said vertically arranged air duct.
2. In a device of the kind described the combination of a member providing a wall of a vertically arranged heat conducting air duct, said member being provided with a passage for a heating medium the passage being arranged longitudinally of said duct and being provided with a liquid receptacle which projects from one face of said member into said vertically arranged air duct, and means for supplying liquid to said receptacle and automatic means for controlling said supply. 70
3. In a device of the kind described the combination of a member providing a wall of a heat conducting air duct, elements providing liquid receptacles formed integral with said member, a second member providing a fluid passage from one receptacle to the other, means for supplying liquid to one of said receptacles, and means in one of said receptacles controlled by the liquid level in said receptacle for controlling the supply of 80 fluid to said receptacles. 85
4. A member adapted to provide an element of a wall of a casing, said wall being comprised of a plurality of said members, each of said members having a fluid passage which extends longitudinally of said member, the opposite ends of said fluid passage being provided with tubular portions adapted to be connected with a similar portion of an adjacent member and one of said members having receptacles provided thereon extending from one face thereof, means for supplying liquid to one of said receptacles, an element providing a liquid passage from one receptacle to the other and means provided in one 90 of said receptacles for controlling said supply. 95
5. In a device of the kind described the combination of a casing, a member providing a wall of said casing and located relatively 100 to the opposite ends of the casing to provide an opening adjacent the opposite ends of the casing, said member having a receptacle projecting from one face thereof into said casing, a receptacle, means for supplying fluid to said first mentioned receptacle, a connection between said receptacles whereby fluid may circulate from said first mentioned receptacle to the second mentioned receptacle and means for controlling flow of fluid 110 to said first mentioned receptacle, said means being controlled by fluid in said second mentioned receptacle. 115
6. A member adapted to provide an element of a wall of a casing, said wall being 120 comprised of a plurality of said members, each of said members having a portion providing a passage which extends longitudinally of said member, the opposite ends of said portions providing said fluid passages being 125 130

provided with tubular portions adapted to be connected with similar portions of adjacent members, certain of said members having elements providing receptacles, means providing a connection between receptacles of adjacent members, means for supplying fluid to one of said receptacles and a member providing a fluid passage between receptacles of one of said members and means provided in one of said receptacles for controlling flow of fluid through said supply.

7. In a device of the kind described the combination of a member adapted to provide a wall of a heat conducting air duct, said member being provided with a passage for a heating medium and being provided with a plurality of receptacles for liquid, the receptacles being arranged upon one side of said member to project into said air duct, a member providing a fluid connection between said receptacles and one of said receptacles providing means for the reception of an element for controlling flow of liquid to said receptacles.

25 8. In a device of the kind described the combination of a member providing a wall of a heat conducting air duct, said member being provided with a passage for a heating medium and being provided with a liquid receptacle which projects from one face of said member into said air duct and heat radiating fins projecting from said member into said air duct.

9. In a device of the kind described, the combination of a member adapted to provide a wall of a vertically arranged heat conducting casing having an air inlet opening adjacent the lower end and an air outlet opening adjacent the upper end, said member having an element providing a passage for a heating medium, means for supplying moisture, said means including a fluid passage associated with said member, a receptacle arranged relatively to said member to receive moisture discharged from said passage, and means in said receptacle for controlling said means for supplying said moisture.

In witness whereof, I hereunto subscribe my name this 27th day of March A. D., 1930.
60 ARTHUR B. MODINE.
